US00D710855S

(12) **United States Design Patent**
Akana et al.

(10) **Patent No.:** US D710,855 S
(45) **Date of Patent:** ** *Aug. 12, 2014

- (54) **HOUSING FOR AN ELECTRONIC DEVICE**
(71) Applicant: **Apple Inc.**, Cupertino, CA (US)
(72) Inventors: **Jody Akana**, San Francisco, CA (US); **Bartley K. Andre**, Menlo Park, CA (US); **Jeremy Bataillou**, San Francisco, CA (US); **Sean Stewart Corbin**, San Jose, CA (US); **Daniel J. Coster**, San Francisco, CA (US); **Daniele De Iuliis**, San Francisco, CA (US); **Jeremy Contini Franklin**, San Francisco, CA (US); **Kevin David Gibbs**, Menlo Park, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Stephen McClure**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugen Anthony Whang**, San Francisco, CA (US); **Rico Zörkendörfer**, San Francisco, CA (US)
(73) Assignee: **Apple Inc.**, Cupertino, CA (US)
(*) Notice: This patent is subject to a terminal disclaimer.
(**) Term: **14 Years**
(21) Appl. No.: **29/438,868**
(22) Filed: **Dec. 4, 2012**

CLAIM

(57) The ornamental design for a housing for an electronic device, as shown and described.

DESCRIPTION

FIG. 1 is a bottom front perspective view of a housing for an electronic device showing our new design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The shade lines in the Figures show contour and not surface ornamentation.

The broken lines in the Figures show portions of the housing for an electronic device which form no part of the claimed design.

1 Claim, 6 Drawing Sheets
